UNITED STATES PATENT OFFICE.

LOTHAR R. ZIFFERER, OF NEW YORK, N. Y.

EXPANSION-BOLT.

1,138,345.

Specification of Letters Patent.

Patented May 4, 1915.

Application filed November 25, 1914. Serial No. 873,968.

To all whom it may concern:

Be it known that I, LOTHAR R. ZIFFERER, a citizen of the United States, residing at New York, in the county of New York and State of New York, have invented certain new and useful Improvements in Expansion-Bolts, of which the following is a specification.

This invention relates to expansion bolts 10 formed of a relatively hard material, such as malleable iron, and is concerned with certain exterior and interior features of shield construction.

My invention has for one of its principal 15 objects the provision of elements upon the shield exterior so formed, arranged, and proportioned as to allow an easy insertion of the device into its intended aperture, to resist withdrawal from the aperture, and 20 prevent rotary movement within the aperture.

The invention further is concerned with the mechanical construction and arrangement of these exterior elements to the end 25 that the forces of compression exerted upon the shield may best be withstood.

Other objects and uses will also appear from a detailed description of the invention as hereinafter set forth.

30 There are many materials in which expansion bolts may be anchored. Brick, tile, concrete, and masonry of all kinds are among the most common. Shields for expansion bolts have heretofore been designed to resist 35 withdrawal from, and rotation within, apertures in materials such as those mentioned. So far as I am aware, these ends have not been satisfactorily accomplished, due principally, to neglect of factors which are always 40 present.

It is to provide an expansion bolt the structural elements of which are so arranged as to resist movement and pressure of every kind, that the present invention is designed.

45 In the drawing: Figure 1 is a view of an expansion bolt embodying my invention, shown partially inserted within an aperture; Fig. 2 is a view similar to Fig. 1, showing the device completely inserted within 50 an aperture; Fig. 3 is an end view of a slightly modified form of device shown inserted within an aperture; Fig. 4 is an enlarged transverse section taken on line 4-4 of Fig. 2.

55 In the drawing is shown a shield represented for convenience as formed of two

complementary sections 6 and 7, held operatively together at their outer ends by means of clamps 8, engaging within notches 9. The shield exterior at its inner end throughout 60 the plane where expansion occurs is provided with annular ribs or projections 10, disposed transversely of the shield axis, and intended to be embedded within the material surrounding the hole when expansion is produced. It is manifest that such transverse elements serve primarily to resist longitudinal movements of the shield within its aperture. 65

Each of the shield sections at its outer end 70 is provided with a number of projections or longitudinal ribs 11 of substantially the same elevation as the transverse ribs 10. A single projecting fin 12 is arranged symmetrically with respect to the other ribs 11, 75 this being of greater elevation, and preferably inclined as appears best in Figs. 1 and 2. The disposition of this fin is substantially midway between the meeting faces of the shield sections. The arrangement shown 80 in Fig. 3 is the same as in Fig. 2, except that the fin 12 is duplicated on the opposite side of the shield, the other elements remaining the same.

Installation of the present expansion bolt 85 within an aperture of proper dimensions is readily effected up to the point where the ribs 11 encounter the hole. Further insertion is possible only by forcibly advancing the shield, as by the use of a hammer. It is 90 manifest that complete insertion must result in one of two things: either (1) the outer end of the shield must be distorted and crushed inwardly for the aperture to accommodate the projecting fin, or (2) a shallow furrow or groove must be cut within the wall surrounding the aperture as the fin advances. 95

The use of a plurality of longitudinal ribs, each intended to cut a slight furrow into 100 an aperture has heretofore been suggested, as I am aware, but this is not a practical construction, as experience has demonstrated that the number of furrows to be so cut must be multiplied so many times as to make such 105 a furrow-cutting action practically impossible. Also I have known of expansion shields, substantially cylindrical at the outer end, except for the provision of a single projecting fin, which shields were found to be 110 unsatisfactory because they would be collapsed, crushed, or distorted when driven

into operative position within apertures. In an expansion shield constructed in accordance with my invention, it is possible for the single fin 12 to cut the required furrow 5 when a plurality of such furrows could not be readily so cut, and to resist successfully the tendency to crush or collapse the shield sections at their outer ends.

The purpose of the ribs 11, it should be 10 explained, is to present relatively sharp edges against the interior of the aperture which shall, by a frictional engagement, resist turning of the shield when a bolt, screw, or lag screw is inserted to cause expansion. 15 The projecting fin 12 enhances greatly the resistance against rotation of the shield, by being forcibly interlocked within the wall as distinguished from the frictional engagement of the ribs 11. It is apparent, of 20 course, that the pressure exerted on the outer end of the shield by the forcible entry of the fin into the anchoring body is distributed to each of the other ribs 11, so the pressure of these ribs against the inside of the 25 aperture is greatly increased.

It appears best from Fig. 4 that I have provided altogether eight longitudinal ribs, one of which is the fin 12. This number, and the disposition of the same in the manner illustrated, I prefer to any other. This 20 is due partly to considerations of expediency in manufacture, and also to the ability of such an arrangement of ribs to withstand

effectively the pressure resulting from embedding of the fin 12 within the wall. Between these ribs the panels or spaces are flattened to eliminate curvatures in construction. When, from the direction of this fin, forces are exerted inwardly sufficient to crush, collapse, or distort the outer end of 40 the shield, the pressure is distributed over the outer end of each shield half through the straight-line panels which act as braces, and thrust back against the aperture walls at seven different points. The distances between such points of pressure thrust are so close, and the material so shaped to serve as bracing elements, that bending or buckling of the shield cannot take place—a fault hitherto common in the constructions 45 I have mentioned.

I claim:

An expansion bolt shield having its outer end slightly less in diameter than the remainder of the shield body, a projecting fin 55 on the outer end of the shield extended above the shield body, and other projections disposed parallel with the shield axis of substantially even height with the shield body, all of the said projections being arranged 60 not more than 45 degrees apart, substantially as described.

LOTHAR R. ZIFFERER.
